ELECTRIC SHAVER

Simon P. Winther, Chicago, Ill., assignor of forty per cent to Leslie Krueger, Chicago, Ill.

Application December 18, 1952, Serial No. 22,752

Term of patent 14 years
(Cl. D22—3)

To all whom it may concern:

Be it known that I, Simon P. Winther, a citizen of the United States, residing at Chicago, in the county of Cook and State of Illinois, have invented a new, original, and ornamental Design for an Electric Shaver, of which the following is a specification, reference being had to the accompanying drawing, forming part thereof.

The side of the electric shaver not shown is of the same appearance as the side illustrated.

I claim:
The ornamental design for an electric shaver, as shown and described.

SIMON P. WINTHER.
